(57) **CLAIM**

The ornamental design for a cover for ceiling fan and light, as shown and described.

DESCRIPTION

FIG. 1 is a top, front side perspective view of a cover for ceiling fan and light, showing my new design;

FIG. 2 is a bottom, front side perspective view thereof;

FIG. 3 is a front elevational view thereof;

FIG. 4 is a top plan view thereof; and,

FIG. 5 is a bottom plan view thereof.

The back, right, left side views are omitted as they are identical with the front view.

The broken lines shown in the drawings illustrate portions of the cover for ceiling fan and light that form no part of the claimed design.
